Hart Anderson

UNITED STATES PATENT OFFICE.

GEORGE DEVOLL, OF BOSTON, MASSACHUSETTS.

STOCKING-SUPPORTING CLASP.

No. 841,127.

Specification of Letters Patent.

Patented Jan. 15, 1907.

Application filed March 26, 1906. Serial No. 308,035.

To all whom it may concern:

Be it known that I, GEORGE DEVOLL, a citizen of the United States, residing at Boston, in the county of Suffolk and State of Massachusetts, have invented certain new and useful Improvements in Stocking-Supporting Clasps; and I do hereby declare the following to be a full, clear, and exact description of the invention, such as will enable others skilled in the art to which it appertains to make and use the same.

The present invention relates to clasps for stocking-supporters.

As such clasps are now commonly made they comprise a plate carrying a headed stud or button, over which the fabric of the stocking is laid, and a metallic loop or bail, which is passed over the headed stud or button and clamps the fabric of the stocking.

The use of the clamping-bail has been found objectionable for several reasons, particularly when fine silk stockings are used, chiefly because there is great danger of the clamping action of the bail tearing the stocking. It is to obviate this difficulty that I have produced my improved clasp, which can be used with the finest silk or lace stockings without in any manner injuring them, and at the same time produce a clasp which is equally effective as a supporter as the usual device referred to.

To the above ends my invention consists of the improved stocking-supporting clasp which will now be described and claimed.

My invention is shown in the accompanying drawings, in which—

Figure 1 shows one form of stocking-supporter provided with my improved clasps; and Fig. 2 shows in front elevation one of the clasps in use, showing the manner of engaging the stocking.

Similar reference characters will be employed in the specification and drawings to designate corresponding parts.

In the drawings, A represents a form of stocking-supporter of a well-known type, comprising a waistband or belt a and the depending elastic straps b, to which are adjustably secured by the buckles c the elastic tabs d.

Each of the tabs d is provided with one of my improved supporting-clasps, which comprises, preferably, a metallic plate e, which may be secured in any suitable manner to the tab d, as by providing the plate e with the slots f, g, and h, through which the end of the

tab may be laced and secured by sewing, all in a manner well known in this art.

The plate e carries a headed button or stud i, which may be made of any suitable material and attached to the plate e in any convenient manner. Coöperating with the headed stud i to hold the stocking are the tapes or ribbons t, which may be of any suitable textile fabric, preferably of silk ribbon of any desired color to match or contrast with the color of the supporter. This tape or ribbon t is fastened to the upper part of the plate e in such manner as to cause its two ends t' and t'' to hang down upon opposite sides of the headed stud or button; and it is preferably detachably secured to the plate by doubling a strip of ribbon of suitable length and passing the doubled portion through a hole e' in the plate e and thence passing the free ends of the tape or ribbon downward through the doubled portion upon the outside of the plate, all as clearly shown in the drawings. By making the tapes or ribbons removable or detachable they may be readily replaced when worn out or they may be changed as desired, whereby the various colors may be used according to the taste or desire of the wearer.

Fig. 2 shows the manner of using my improved clasp. The stocking s being laid over and upon the headed stud or button in the usual manner, thence one of the tapes or ribbons t' will be wrapped or wound one or more times around the stocking fabric in one direction and drawn tightly about the shank of the stud or button beneath the head, and the other tape or ribbon t'' will be wrapped or wound about the stocking fabric and the shank of the stud or button in the opposite direction. Then the two ends will be tied in a bow beneath the stud or button, as clearly shown in Fig. 2, thus securely fastening the stocking and without danger of tearing it.

The bow-knot will preferably be tied without the usual preliminary knotting or crossing of the ends of the tapes or ribbons, so that a pull upon one of the ends will release the bow and permit the ready disengagement of the stocking from the clasp.

It is thought that my invention has been sufficiently described to enable one skilled in the art to understand its construction and mode of operation; but before proceeding to claim the same I want to say that I do not consider my invention as limited to the details shown and described, as, so far as I am

aware of the state of the art, I am the first to produce a stocking-supporting clasp having a headed button or stud and co-operating flexible tapes or ribbons.

5 Having described my invention, I claim as new and desire to protect by Letters Patent of the United States—

1. A stocking-supporting clasp comprising a plate, a headed stud or button mounted thereon and flexible tapes or ribbons secured to said plate and adapted to secure the stocking to the headed stud or button, substantially as described.

2. A stocking-supporting clasp comprising a plate, a headed stud or button mounted thereon and flexible tapes or ribbons detachably secured to said plate and adapted to secure the stocking to the headed stud or button, substantially as described. 15

In testimony whereof I affix my signature 20 in presence of two witnesses.

GEORGE DEVOLL.
